US0D1081418S

(12) **United States Design Patent** (10) **Patent No.:** **US D1,081,418 S**
(45) **Date of Patent:** **** Jul. 1, 2025**

(54) **TRACKER HOUSING**(71) Applicant: **Elevation Lab, Inc.**, Portland, OR (US)(72) Inventors: **Casey Hopkins**, Portland, OR (US);
Jacob Hull, Portland, OR (US)(73) Assignee: **Elevation Lab, Inc.**, Portland, OR (US)(***) Term: **15 Years**(21) Appl. No.: **29/911,420**(22) Filed: **Sep. 1, 2023****Related U.S. Application Data**

(62) Division of application No. 29/885,160, filed on Feb. 21, 2023, now Pat. No. Des. 1,003,747.

(51) **LOC (15) Cl.** ..... **10-04**(52) **U.S. Cl.**USPC ..... **D10/70**(58) **Field of Classification Search**USPC D10/46, 47, 50, 65, 70, 71, 81, 100, 103

(57) **CLAIM**

The ornamental design for a tracker housing as shown and described.

DESCRIPTION

FIG. 1 is a top, right, front isometric view of a tracker housing showing the new design;

FIG. 2 is a bottom, left, rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

1 Claim, 5 Drawing Sheets
